UNITED STATES PATENT OFFICE.

JOHN C. McLAUGHLIN, OF JERSEY CITY, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,209,865.

Specification of Letters Patent. Patented Dec. 26, 1916.

Application filed July 22, 1913. Serial No. 780,429.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to means for facilitating the introduction and adjustment of bill-heads or other small work-sheets, into the carriages of typewriting machines.

The improvement comprises a paper guide or chute which may be supported as an auxiliary from the rear of the usual paper-shelf at the introductory side of a typewriting machine. The work-sheet is laid on the guide between lateral gages which position it squarely with reference to the platen, and is then slid down the guide to be fed around the platen, thereby obviating the loss of time usually required to adjust and manipulate the work-sheet. This auxiliary sheet-guide is preferably constructed of two telescoping sections, which may readily be expanded to separate its side gages more or less, to accommodate various widths of work-sheets. Preferably the guide may be swung back behind the usual paper-shelf out of the way when an ordinary work-sheet is to be inserted, whereby the relative adjustment of said side gages may be preserved, for subsequent use.

Other features and advantages will hereinafter appear.

In the accompanying drawings, Figure 1 is a perspective view showing my improvements applied to the usual form of an "Underwood" platen frame or carriage. Fig. 2 is a side elevation of the parts shown in Fig. 1. Fig. 3 is a fragmentary rear view of the improved auxiliary paper guide, and the ordinary paper-shelf, showing the method of mounting the former and the means for locking the sections of the guide together. Fig. 4 is a view of one of the carriers upon which the auxiliary guide is mounted, showing the position of said carrier when the said guide is swung behind the usual paper-shelf. Fig. 5 is a view similar to Fig. 4, with the carrier in working position.

The usual platen 1 is mounted between

platen frame ends 2, held together by a paper-table 3 extending along the rear of 55 the platen.

The improvement comprises a special paper-shelf or chute 4, with upturned side edges forming lateral gages or guides 5 for the work-sheets, and is supported by brackets 6, pivotally mounted on ears 7 of carriers 8. This member 4, which may partly overlie the paper-table 3, forms a long support, guide or rest, upon which the work-sheet may be laid between the lateral gages 65 5 preparatory to being fed around the platen; the sheet being accurately positioned without the exercise of care on the part of the operator.

The auxiliary shelf 4 may be adjusted 70 to any desired point along the writing line, by shifting it bodily with the carriers or mounts 8. These carriers or mounts are sliding, and are splined to a rail 9 by pins or rolls 10, which are held in slots 11 of 75 the carriers and forced into a groove 12, running along the rail 9 by bow springs 13. The rail 9 is supported by brackets 14 extending from the platen frame ends 2, directly beneath a bead or rolled rim 15 usually formed on the paper-table 3.

A spring 16, attached to the ear 7 of each carrier 8 and coiled around the pivot pin which connects the carrier to the respective bracket 6 with its other end bearing against 85 the bracket 6, normally keeps the lower edge 17 of the auxiliary paper-table 4 against the surface of the paper-table 3.

The auxiliary guide or table 4 is preferably formed of two sections 18, 19, which 90 may telescope to permit the side-edges or lateral guides 5 to be adjusted for various widths of work-sheets. The upper edges of this table 4 are bent over to form stiffening ribs 20, and the section 18 is slotted to receive a lock nut 21, which may be drawn up by a screw 22 in the section 19 (Fig. 3), to clamp the sections together and prevent accidental relative shifting. The lower edge 17 of the section 19 may be bent upwardly 95 100 as shown to form a guiding flange, which, with the body of the section provides a guiding groove for the lower edge of the section 18.

A slight rearward bend along a line 23 105 of the auxiliary table 4, serves to counter-

act the tendency of a long work-sheet to spring or bulge forward and tumble over the front of the machine, by permitting the work-sheet to assume a more inclined position at the introductory side of the machine.

The auxiliary paper table may at any time be swung back out of the way, by forcibly rotating the carriers 8 on the rail 10 9, whereupon the springs 16 will bring the said auxiliary table to a position against the rear of the paper table 3, as shown in Fig. 4.

Variations may be resorted to within the 15 scope of the invention, and portions of the improvements may be used without others.

Having thus described my invention, I claim:

1. In a typewriting machine, the combination with a platen and a paper-shelf at 20 the introductory side of the platen forming a chute for the work-pieces, of a rail extending along said shelf, carriers splined to said rail, two telescoping auxiliary paper- 25 shelf sections hinged to said carriers to cooperate with said paper-shelf, guides along a side edge of each of said sections, and means for locking said sections together.

2. In a typewriting machine, the combination 30 with a platen and a paper-shelf at the introductory side of the platen, of a rail extending along said shelf, carriers splined to said rail, an auxiliary paper-shelf forming a chute for work-sheets as they are advanced to the platen, said auxiliary shelf 35 hinged to said carriers and comprising two gaging sections provided along their outer edges with gages for the lateral edges of the work-sheets, said sections relatively movable 40 laterally to move the gages toward and from each other and having their inner edges overlapped to form a continuous support for the work-sheets between the gages, and means to permit said sections to be moved 45 unitedly into an inoperative position.

3. In a typewriting machine, the combination with a rotary platen, of a paper-shelf at the introductory side thereof comprising sections, and a slidable connection between 50 said sections, rendering them evenly adjustable in a single operation toward and from each other, said sections carrying gages for the side edges of a work-sheet and forming a chute for guiding the work-sheet to the introductory side of the platen.

4. In a typewriting machine, the combination with a rotary platen, of a paper-shelf at the introductory side thereof comprising sections, and a slidable connection between 55 said sections, rendering them evenly adjustable in a single operation toward and from each other, said sections carrying gages for the side edges of a work-sheet, and adjustable together along the platen, thereby forming 60 a chute adjustable in width, and also

adjustable bodily along the platen, said chute serving to gage and guide the work-sheets as they are introduced to the platen.

5. In a typewriting machine, the combination with a rotatable platen, of a paper-shelf forming a chute for supporting and guiding work-sheets at the introductory side of the platen and comprising overlapping sections, each section provided with an end-flange forming a gage for the work-sheets, and a slidable connection between 70 said sections, whereby they are laterally and evenly adjustable relatively to each other in a single operation.

6. In a typewriting machine, the combination with a rotatable platen, of a paper-shelf comprising a pair of substantially-counterpart sections, a slidable connection directly between said sections, rendering them adjustable in a single operation to 80 vary the width of the shelf, and means to lock the sections in adjusted position, said paper-shelf forming a chute at the introductory side of the platen to support and guide the work-sheets to the platen.

7. In a typewriting machine, the combination with a platen, of a paper-shelf comprising sections, a slidable connection between said sections, rendering them relatively and evenly adjustable in a single operation to vary the width of the shelf, means to hold the sections in adjusted position, and a support on which said shelf is mounted for bodily adjustment in the direction of the platen axle, said shelf forming a chute 90 at the introductory side of the platen to support and guide the work-sheets to the platen.

8. In a typewriting machine, the combination with a rotatable platen, of a paper-shelf comprising sections, a slidable connection between said sections, rendering them relatively and evenly adjustable in a single operation to vary the width of the shelf, gages on said sections, and a rod parallel 105 with the platen on which said shelf is mounted and longitudinally adjustable, said shelf forming a chute at the introductory side of the platen to support and guide the work-sheets to the platen.

9. In a typewriting machine, the combination with a rotatable platen, of a paper-shelf comprising overlapping sections, a slidable connection between said sections, rendering them evenly adjustable in a single 115 operation toward and from each other and formed at their outer sides with paper gages, supports to which said sections are pivotally attached, and a rod parallel with the platen axle on which the supports are 120 adjustably mounted, said shelf forming a chute at the introductory side of the platen to support and guide the work-sheets to the platen.

10. In a typewriting machine, the combi- 130

- nation with a rotatable platen and a platen frame comprising a paper-shelf at the introductory side of the platen, of an auxiliary paper-shelf forming a chute overlying the
- 5 1. first-mentioned paper-shelf and comprising sections, a slideable connection between said sections, rendering them relatively and evenly adjustable in a single operation to vary the width of the auxiliary shelf, gages
- 10 2. on said sections for the side edges of a work-sheet, and a hinge support for the auxiliary shelf permitting it to be swung to an inoperative position, allowing the use of said first-named shelf.
- 15 3. 11. In a typewriting machine, the combination with a rotatable platen and a paper-shelf at the introductory side thereof, of an auxiliary shelf comprising overlapping sections forming a chute overlying the first-
- 20 4. named shelf, a slideable connection between said sections, rendering them evenly adjustable in a single operation toward and from each other to vary the width of the auxiliary shelf, and a support along which the auxiliary shelf is adjustable in the direction of the platen axis, said auxiliary shelf being pivotally mounted to be swung away from the first-named shelf, to permit the use of the latter.
- 25 5. 12. As an article of manufacture, a paper-shelf comprising a body portion of sheet material consisting of overlapping sections, a slideable connection between said sections, rendering them evenly adjustable in a single operation toward and from each other, means to lock said sections in adjusted position, and side-flanges turned up from said body portion to form gages for the margin edges of a work-sheet, said body portion
- 30 6. having its direction changed along a line transverse to the side-flanges, so that the upper part of the paper-supporting surface is inclined to the lower part.
- 35 7. A paper-shelf comprising overlapping sections of sheet material, each section having an outer flange forming a paper gage and each section provided with an additional flange, said additional flanges overlapping, and a locking device to clamp said additional flanges together, and thereby hold said sections in adjusted position, the paper-engaging surface of the shelf having its direction changed along a line transverse to said outer flanges, so that the upper part of
- 40 8. said surface is inclined to the lower part.
- 45 9. 14. In a typewriting machine, the combination with a platen and a paper-shelf at the introductory side of the platen, of a rail extending along the rear of said paper-shelf, carriers shiftable along said rail, an auxiliary paper-shelf hinged to said carriers, said auxiliary paper-shelf comprising two telescoping sections, a slideable connection between said sections, permitting relative lateral movement thereof in unison, and a
- 50 10. guide along one side of each section, said guides maintaining true guiding positions for the work-sheets in the variable adjustments of said sections.
- 55 11. In a typewriting machine, the combination of a paper-shelf forming a chute for work-sheets at the introductory side of the platen and comprising right and left-hand sections, a gage upon each section, respectively, for the opposite side edges of work-sheets of variable widths, means slideably and independently supporting said sections at corresponding ends thereof, and means slideably connecting said sections at their other ends to permit lateral adjustments thereof in a single operation with relation to each other and the platen, to establish an introductory gaged position for the work-sheets.
- 60 12. In a typewriting machine, the combination of a paper shelf forming a chute for work-sheets at the introductory side of the platen and comprising right and left-hand sections, a gage upon each section, respectively, for the opposite side edges of work-sheets of variable widths, means slideably and independently supporting said sections at corresponding ends thereof, means slideably connecting said sections at their other ends to permit lateral adjustments thereof in a single operation with relation to each other and the platen, to establish an introductory gaged position for the work-sheets, and means for securing said sections as adjusted.
- 65 13. In a typewriting machine, the combination of a paper-shelf forming a chute for work-sheets at the introductory side of the platen and comprising right and left-hand sections, a gage upon each section, respectively, for the opposite side edges of work-sheets of variable widths, means slideably and independently supporting said sections at corresponding ends thereof, and means slideably connecting said sections at their other ends to permit lateral adjustments thereof in a single operation with relation to each other and the platen, to establish an introductory gaged position for the work-sheets; said slideable connecting means having locking means capable of securing or releasing said sections in a single operation.
- 70 14. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 75 15. In a typewriting machine, the combination of a paper-shelf forming a chute for work-sheets at the introductory side of the platen and comprising right and left-hand sections, a gage upon each section, respectively, for the opposite side edges of work-sheets of variable widths, means slideably and independently supporting said sections at corresponding ends thereof, and means slideably connecting said sections at their other ends to permit lateral adjustments thereof in a single operation with relation to each other and the platen, to establish an introductory gaged position for the work-sheets.
- 80 16. In a typewriting machine, the combination of a paper shelf forming a chute for work-sheets at the introductory side of the platen and comprising right and left-hand sections, a gage upon each section, respectively, for the opposite side edges of work-sheets of variable widths, means slideably and independently supporting said sections at corresponding ends thereof, means slideably connecting said sections at their other ends to permit lateral adjustments thereof in a single operation with relation to each other and the platen, to establish an introductory gaged position for the work-sheets, and means for securing said sections as adjusted.
- 85 17. In a typewriting machine, the combination of a paper-shelf forming a chute for work-sheets at the introductory side of the platen and comprising right and left-hand sections, a gage upon each section, respectively, for the opposite side edges of work-sheets of variable widths, means slideably and independently supporting said sections at corresponding ends thereof, and means slideably connecting said sections at their other ends to permit lateral adjustments thereof in a single operation with relation to each other and the platen, to establish an introductory gaged position for the work-sheets; said slideable connecting means having locking means capable of securing or releasing said sections in a single operation.
- 90 18. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 95 19. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 100 20. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 105 21. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 110 22. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 115 23. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 120 24. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 125 25. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.
- 130 26. In a typewriting machine, the combination with a platen, of a paper-shelf forming a chute for work-sheets at the introductory side of the platen and comprising right and left-hand gage sections, a support for said sections on which they may slide independently, and a slideable connection between said sections whereby they are adjustable relatively to each other and to the platen in a single operation, to establish an introductory gaged position for the work-sheets.

19. In a typewriting machine, the combination with a platen, of a paper-shelf forming a chute for work-sheets at the introductory side of the platen and comprising right and left-hand gage sections, a support for said sections on which they may slide independently, and a slidable connection between said sections whereby they are adjustable relatively to each other and to the platen in a single operation, to establish an introductory gaged position for the work-sheets; said slidable connection having fastening means capable of securing and releasing said sections in a single operation.
20. A paper-shelf comprising right and left-hand sections of sheet material, each section having an outer flange forming a gage, said sections being adjustable to and from each other to provide a lateral confining gage for work-sheets of variable widths, and said sections in their variable positions of adjustment unitedly providing a laterally continuous work-sheet support, the paper-engaging surface of the shelf having its direction changed along a line transverse to said outer flanges, so that the upper part of said surface is inclined to the lower part.
21. A paper-shelf comprising right and left-hand sections of sheet material, each section having an outer flange forming a gage, said sections being adjustable to and from each other to provide a lateral confining gage for work-sheets of variable widths, and said sections in their variable positions of adjustment unitedly providing a laterally continuous work-sheet support, and means for securing said sections as adjusted, the paper-engaging surface of the shelf having its direction changed along a line transverse to said outer flanges, so that the upper part of said surface is inclined to the lower part.
22. In a typewriting machine, the combination with a platen, of means at the introductory side of the platen for supporting and guiding work-sheets as they are advanced to the platen, said means comprising side gages for the edges of the work-sheets, and overlapping connecting devices fixed respectively to the side gages and forming a slidable connection between said gages, rendering them evenly adjustable in a single operation toward and from each other.
23. In a typewriting machine, the combination with a platen, of means at the introductory side of the platen for supporting and guiding work-sheets as they are advanced to the platen, said means comprising side gages for the edges of the work-sheets, overlapping connecting devices fixed respectively to the side gages and form-
- ing a slidable connection between said gages, rendering them evenly adjustable in a single operation toward and from each other, means to lock said gages in their relative position of adjustment, and a support on which said gages are mounted for united adjustment lengthwise of the platen while locked against relative movement.
24. In a typewriting machine, the combination with a platen, of means at the introductory side of the platen for supporting and guiding work-sheets as they are advanced to the platen, said means comprising right and left-hand gage sections for gaging the lateral edges of the work-sheets, a support for said sections on which they may each slide independently of the other, and telescoping connecting members fixed respectively to the gage sections and forming a slidable connection between said sections whereby they are adjustable relatively to each other and to the platen in a single operation.
25. In a typewriting machine, the combination with a platen, of means at the introductory side of the platen for supporting and guiding work-sheets as they are advanced to the platen, said means comprising right and left-hand gage sections for gaging the lateral edges of the work-sheets, a support for said sections on which they may each slide independently of the other, and telescoping connecting members fixed respectively to the gage sections and forming a slidable connection between said sections whereby they are adjustable relatively to each other and to the platen in a single operation, said slidable connection having fastening means capable of securing or releasing said sections in a single operation.
26. In a typewriting machine, the combination with a rotary platen, of an upwardly and rearwardly inclined paper shelf at the introductory side of the platen, said shelf comprising sections of sheet material, each section having an outer flange forming a side gage for the edge of a work-sheet, said sections overlapping to form a continuous support for the sheets between the gages and having a slidable connection for adjustment of the gages toward and from each other, said shelf having its inclination changed along a line transverse to said gages, so that the rearward inclination of the upper sheet-engaging portion of the shelf is greater than that of the lower portion of the shelf.
